BEAM DEFLECTION CONTROL FOR
CATHODE-RAY DEVICES

Antony Wright, Drexel Hill, Pa., and Edwin L. Clark, Collingswood, N. J., assignors to Radio Corporation of America, a corporation of Delaware

Application September 26, 1946, Serial No. 699,536

16 Claims. (Cl. 315—22)

1

This invention is directed to electronic circuits for use particularly in relation to the control of the deflection of a cathode ray beam developed within the cathode ray tube and forms a continuation-in-part of our U. S. application Serial No. 584,108, filed March 22, 1945, now abandoned. As such, the invention finds primary application in connection with television apparatus, although it will be apparent that the invention may find use also in connection with certain forms of oscillograph devices where electron beam deflection is controlled from an external source.

Particularly in connection with television developments, it has been found that in order to provide satisfactory images for viewing at the receiving point, the synchronization must be maintained very accurate at all times. Accordingly, noise disturbances, such, for instance, as those due to ignition troubles introduced from nearby disturbing sources or even remote sources may frequently have a very detrimental effect on the viewed image. Where there is a disturbance effect on the deflection, due to ignition noises, many times due to the effect of diathermy and other forms of spurious signals, the resultant disturbances, all of which will hereafter be referred to for convenience as the "noise" signals, frequently add to the synchronizing pulses, ordinarily termed the "sync" pulses, and destroy both the synchronization and interlace of the viewed image. Further, the noise signals, when combined with the sync signals, or when occurring immediately prior to the time of receipt of sync signals, often cause the local oscillators or sync control channels to trace or trigger at times which precede the desired sync pulses and, thus, frequently cause different scanning paths, which, literally, "tear out" and destroy the resultant image.

Accordingly, it becomes one object of this invention to provide a system for synchronizing television or oscillographic apparatus which will have a high degree of immunity to noise impulses.

A further object of the present invention is that of providing a synchronizing system in which it is possible to retain the maximum resolution of image detail under conditions of low signal-to-noise ratio, since it has been found that the apparent resolution of an image is very greatly improved where the synchronizing effects are rigorously held to some predetermined standard and constant rate.

Another important object of the invention is that of providing a form of synchronization and

control of the electron beam deflection of an image producing cathode ray tube which will preserve the desired line structure of the image raster irrespective of the influence of electrical disturbances.

Other objects of the invention are those of providing improved forms of synchronizing action wherein the effects of received synchronizing pulses may be, in effect, held over or subjected to what might be termed "flywheel action," whereby only the desired sync signals shall have effect on the control and the operation of the deflection channel.

Other objects of the invention are those of providing a television circuit particularly useable in the deflection channel which shall embody the principles of an automatic frequency control operating in such a way that the deflection is improved to a considerable degree over that normally obtainable with the so-called "triggered" synchronizing circuit control.

Other objects of the invention are those of providing an improved form of deflection control and synchronizing circuit which has greater efficiency in its operation; is more stable in its control; is relatively cheap to construct; is positive in its operation; and, at the same time, overcomes many defects heretofore found to exist in prior art arrangements.

Still other objects of the invention will become apparent and suggest themselves to those skilled in the art to which the invention is directed when the accompanying drawings are considered in the light of the description to follow.

In the drawings, Fig. 1 represents in block diagrammatic form one suitable circuit by which the invention in question may be practiced;

Fig. 2 is a circuit wherein the principles of Fig. 1 are incorporated;

Fig. 3 comprises two curves to show the operation of the system under one condition;

Fig. 4 consists of a set of two curves to show the operation of the system under other conditions; and

Fig. 5 represents a modification of the circuit of Fig. 2.

In the past, it has been customary, in connection with some types of synchronization, to provide a so-called form of automatic frequency control where the operation comprised essentially a phase detector, a suitable filter, and a D. C. amplifier which was arranged to supply its output to control a scanning oscillator, the output of which, in turn, was fed back to the phase detector. In this way, essentially a triangular

2

shaped wave was supplied in phase to each of a pair of diodes forming the phase detector. To these triangular waves the synchronizing pulse was added in both positive and negative polarity. Variances in the output of the phase detector produced by relative phase changes in the two supplied waves caused a suitable voltage to be applied to the D. C. amplifier to control, in turn, the frequency of the scanning oscillator.

The invention herein to be set forth, however, departs from such forms of arrangement as were incorporated in the prior art through the development of substantially sine wave voltages which are relatively easy to control, which can readily be stabilized, and which may serve as the triggering control instrumentality by which a substantially normally and customarily used form of sawtooth wave generator may be controlled to supply its output to the normal power output tube for controlling the cathode ray beam deflection in at least one direction on the image raster.

The invention as disclosed, particularly by the block diagram arrangement of Fig. 1, and as it will be described in later reference herein to that figure, comprises essentially the combination of a stable oscillator, a reactance tube connected in shunt with the oscillator, and a discriminator network adapted to receive sinusoidal waves from the oscillator and incoming sync pulses from a suitable sync separating circuit. The reactance tube unit will be found to be controlled by the development of a direct current pulse or signal which is derived from changes in phase occurring between the impressed incoming sync pulse and the oscillation frequency of the sine wave generated by the oscillator. The oscillator frequency, then, in turn, may be modified under the control of the reactance tube to which the developed D. C. control voltage is applied to vary the reactance tube gain and thus bring about a change in the reactance of the oscillator tank circuit so that the oscillator frequency is brought into proper relationship to the incoming sync pulses and stabilized oscillations, bearing a fixed relationship to the incoming sync pulse, are obtainable. The electron beam deflection circuits proper of the cathode ray tube then are controlled, in turn, from control pulses derived from the stabilized local oscillator.

In its preferred form, the invention will be illustrated as particularly applicable to a deflection control system for cathode ray beams, where the effect of operation is illustrated as applicable to the high frequency or line deflection traces.

The block diagram of Fig. 1 shows the invention schematically combined with a television receiver unit. There the incoming signals, including the video and all necessary accompanying synthesizing signals, as well as audio, where desired, are first supplied to the usual amplifier, selector and converter unit, the output signals from which are then amplified in any suitable intermediate frequency amplifier device. The amplified signals are then demodulated in a unit marked as the second detector to be passed through a suitable video amplifier (usually with D. C. level setting provided) to control the image reproducing tube in such a way that the cathode ray beam produces an intensity modulated pattern or raster on the tube target. This recreates the original image light values.

The detected signals are also supplied to a sync signal separator to select between the video and synthesizing signals. Since this invention is primarily applicable to the horizontal (or line) de-

flection control it will be assumed that the vertical (field or frame) deflection signals are then suitably selected to control the slow speed cathode ray beam deflection through any known form of vertical deflection control, such as the blocking oscillator and output tube arrangement described by Tolsen et al. in U. S. Patent No. 2,101,520, granted December 7, 1937. The other components so far explained and mentioned are well known in general and require no further explanation.

The selected horizontal (that is, the line pulses for providing a control of the rapid motion of the cathode ray beam) are then supplied, as above stated, to the discriminator unit 35 to which the output of the local deflection control oscillator 51 is also supplied, such as above stated. A reactance tube unit 63 is connected across the oscillator tank circuit to change the oscillator frequency with output changes from the discriminator being supplied to the reactance tube unit to vary its transconductance and, in accordance with frequency changes thus brought about, the local oscillator is caused to follow the frequency and phase changes in the controlling pulses. Further details of this control will be mentioned in describing the actual circuit. A horizontal deflection control unit is arranged to control the line or horizontal deflection of the cathode ray beam of the image producing tube when the output signal energy from the local oscillator is supplied, as indicated, as will later be explained in more detail.

The circuit diagrammatically represented by Fig. 2 is one practical embodiment of the schematic showing of Fig. 1 and illustrates the input terminal 11 as the point at which incoming synchronizing or sync signal pulses (conventionally represented above the terminal as the line synchronizing pulses *a* and *b*) are applied. For reasons of simplicity, the vertical input sync pulses are not shown, although in normal present day operation, both the vertical and the horizontal or line sync pulses correspond to those proposed and recommended by the industry and by the National Television System Committee and which are found exemplified and shown on pages 22 and 23 of the book entitled, "Television Standards and Practice" by Donald G. Fink, published by McGraw-Hill Book Company, Inc., New York, 1943. In this form, the sync signals represent those which have been recommended by the National Television System Committee and its panels. It should be understood, however, that the invention functions properly under the control of any suitable recurring sync pulse, but any illustrations herein given are applied, for simplicity, to the new standardized signal form.

The incoming signal pulses are normally applied to the control grid of the sync separator tube 15 by way of the small condenser 17. The cathode 19 of the sync separator tube is preferably connected to ground, which is conventionally represented at 21 throughout the drawings. Suitable operating bias is applied to the separator tube by means of the condenser 17 and the grid leak resistor 23.

The sync separator tube 15 functions in its operation in known manner to separate the sync signal pulses from any remaining portions of the signal. Operating voltages for the sync separator tube 15 are applied through the load resistor 24 from a source of voltage (no voltage source is shown in detail by the drawings but in each instance the source is connected with

indicated polarity and the other source terminal may be assumed to complete the D. C. path through ground) which is connected with its positive terminal connected to the terminal point 25. Any high frequency outputs from tube 15 may be bypassed around a portion of the resistor 24 by way of the high frequency bypass condenser 21.

Output signals from the tube 15 are then supplied by way of a condenser 29 to the conductors 31 and 33. The wave form shown above the tube 15 thus is any representative form of input and not necessarily that applied to the terminal point 11. In the description to follow, the sync pulses will, for reference purposes, be assumed to be positive in the output of the tube 15 as indicated by the arrow 11' on Fig. 2 of the drawing. As similar application of the signal with the image information removed is indicated by the arrow 11' on Fig. 5.

The output energy (or pulses) which appears from the tube 15 and which is applied to the conductors 31 and 33 is then fed to a discriminator tube 35, of which the operation will later be described.

At the same time that line frequency sync pulses, such as *a* and *b*, for instance, are being applied to the discriminator tube 35, the frame or field frequency sync pulses, which are of relatively long duration, as is well known in the art, and which are supplied also to the sync separator tube 15, are fed through the conductor 37 from the output of the tube 15 to control the field or frame deflection control system (not shown) of the apparatus.

The line frequency signals, which are fed by way of conductor 33, are then connected to the center tap 39 of the transformer winding 41 which is to receive a signal from the local oscillator, later to be described. The transformer winding 41 forms an inductive element which is shunted by a capacity 43 and caused to resonate at a frequency which is slightly different than that of the local oscillator, later to be described. Tuning may readily be accomplished, for instance, by the indicated movable iron core, or any other suitable method may be chosen in the alternative. The difference in resonance frequency between the oscillator tank circuit comprising the inductance 53 and the capacitor 55 and the secondary winding 41 of the transformer and its shunt capacity 43 is made use of to obtain a desired phase shift between the oscillator voltage and the sync pulse as appearing at the input terminal 11. This phase shift makes it possible readily to correct the phase between the differentiated discharge pulses, later to be described, and the incoming sync pulse which is obtained whereby a convenient means is provided to correct the picture form.

Thus, the sync or deflection control pulses, which are applied by way of the conductor 33 to the transformer winding 41 are, in turn, supplied to the plate or anode electrodes 44 and 45 of the discriminator tube 35, which plates or anodes are connected to the opposite ends of the transformer winding 41. It will thus become apparent that the incoming sync pulses are applied to each diode plate 44 and 45 in equal amplitude and in phase with each other. Cathode elements 46 and 47 comprise the other electrodes of the tube 35, so that the anode 44 and cathode 46 together form one unidirectional conducting path and the anode 45 with cathode 47 forms a second

unidirectional conducting path. In other words, these electrodes collectively form two separate diodes which, for convenience of illustration and, usually, in operation from the standpoint of cost and convenience, are included in one separate tube envelope. A tube of this type may be one of the form which is known in the art as the 6H6, which is a metal tube and which may have its outer shell grounded.

10 Two resistor elements, indicated as 48 and 49, are connected to the individual cathodes 46 and 47 with their other ends being connected together and also connected to the conductor 31 to which the sync pulse is applied, as above indicated.

15 The local oscillator hereinabove mentioned preferably comprises a tube 51 which is usually in the form of a tetrode and, for example, may be a tube of the type known in the art as the 6K6GT, although this reference, like that given 20 for the discriminator tube, is purely by way of example of one suitable form of tube for the use in question. The oscillator tube 51 is caused to develop substantially sine wave oscillations in a manner which is substantially well known in 25 the art and which may be considered as having been illustrated, in general, by the form of oscillator known as the Hartley type. The oscillatory circuit of oscillator 51 comprises an inductance element 53 which forms the primary winding of 30 the transformer which feeds energy to the secondary coil 41, hereinabove mentioned. The inductive element 53 is shunted by a capacity 55 so that oscillations may be considered as being developed in the circuit at a frequency determined 35 by the inductance and capacity elements. The control electrode 57 of the oscillator tube connects to one end of the oscillatory circuit. The cathode 58 connects to a central point on the inductance element 53. Lastly, the screen electrode 59 connects to the other end of the inductance through the connection made by way of the coupling condenser 61 and ground 21. Thus, a variance in the characteristics of the 40 circuit elements included across the grid to screen grid path will provide oscillation frequency changes, and any oscillations appearing in the oscillatory circuit comprising the inductance 53 and the capacity 55 will, in turn, be transferred by way of the secondary winding 41 to apply 45 voltage to the plate or anode elements 44 and 45 of the discriminator tube 35.

Tuning may be provided, where desired, for the coils 41 and 53 by way of the indicated adjustable iron core elements, as is known in the art. In the manner in which the invention has been shown, it will be apparent that if the oscillator is tuned to approximately the frequency of the incoming sync pulses, such as *a* and *b*, stabilized oscillations will be developed. In this sense, stability is readily improved by making the capacity 55 relatively large in size. If sine wave voltages are induced from the primary winding 53 into the secondary winding 41, it will be observed that these voltages appear 180° out of phase with respect to each other, as applied to the diode plates 44 and 45. It has been seen, from the above explanation, that the separated sync pulses, as appearing in conductor 33, are applied to the center tap 39 of the discriminator coil 41 and, accordingly, appear in phase on each of the plates or anodes 44 and 45 of the discriminator tube 35.

This state of conditions may readily be observed from the showing of Fig. 3 where by curve A, the indicated sine wave voltages are intended

7 to represent the voltage on the diode section 44, 46 due to the oscillator 51, while the curve B of Fig. 3 shows by its sine wave curve the 180° out of phase voltage applied to the diode section 45, 41 into the oscillator 51. If it be assumed that the sync pulse indicated as *a* is such that the relative phase of the sine wave voltages and the sync pulse appear as shown by Fig. 3, then, essentially, a zero D. C. output will appear at the point 62 to be supplied by way of the indicated conductor 66 to control the reactance tube 63, later to be referred to more specifically.

Should the relative phase of the voltages applied to the diode sections due to the oscillator and the voltages applied due to the incoming sync pulse change, as indicated by the second condition shown by Fig. 4 where the sync pulse *a* is now assumed to lead slightly with regard to its position shown in Fig. 3, it will be apparent that more voltage will be produced across the top diode load 48 than appears across the lower diode load 49 for reasons which appear to be readily apparent when the curves on Fig. 4 (A) and Fig. 4 (B) are considered.

If the sync pulse *a* moves to the right from the position shown, it will be apparent by the same reasoning that more voltage appears across the lower diode output resistor 49 than appears across the upper diode output resistor 48. No particular relative relationship has here been chosen for the incoming control sync pulse and the sine wave voltage but it should be understood that in many instances preferred operation is had when the pulse voltage (such as the pulses *a* and *b*, and so on) exceeds the peak-to-peak voltage of the sine wave output of the oscillator as supplied to the diodes.

Depending upon which diode section of the discriminator produces the greater voltage depends the relative polarity or magnitude of the voltage which appears at point 62 and which is then transferred by way of resistor 65, conductor 66 and resistor 67 and across condenser 68 to the input or control electrode 69 of the reactance tube 63 to vary the gain thereof. The reactance tube 63 is connected by way of conductor 71, resistor 73, and capacity 75 to one end of the oscillatory circuit comprising the winding 53 and the condenser 55.

With the arrangement shown whereby the voltage developed at the point 62, for instance, is supplied to control the reactance tube 63 by way of the grid feed resistance and the capacity, it will be observed that a filter and time constant circuit has been provided. The general effect of such a time constant circuit and filter is to filter out any low frequency A. C. from the D. C. control voltage. Such low frequency A. C. might, under some circumstances, come about due to the vertical sync pulses, to name one example.

The cathode of the reactance tube 63 connects to ground 21 and, thus, to the other end of the oscillatory circuit. The plate 19 of the reactance tube 63 connects by way of condenser 81 to the grid or control electrode 51 of tube 51 through the usual grid leak and condenser circuit 82.

From what has been above shown, it will be apparent that the control voltage applied to the control electrode 69 of the reactance tube 63 is such as to restore the original balance condition to the system should the phase of either the sync pulse or the oscillator change within the limits of the system. From what has been above described, it will be apparent that the reactance tube 63 acts as a shunt reactance across the os-

5 cillator coil 53. This reactance, of course, may be varied by a variation in the transconductance of the reactance tube 63, which change may be brought about by a variation of the D. C. voltage applied to the control electrode 69 in accordance with the variation of which diode of the discriminator draws the more current.

10 The reactance tube 63 is so set up that the reactance varies in the direction to keep the oscillator 51 in phase with the sync pulse applied to the terminal 11. The oscillator 51 should preferably be as stable as possible to provide additional smoothness of operation.

15 With the connections shown by Fig. 2, the oscillator tube 51 incorporates also a plate or anode element 83, heretofore not mentioned. The anode or plate 83 connects through the output or load resistor 84 to a terminal point 85 whereat a source of voltage (not shown) is connected with its positive terminal connected to the terminal point 85. The same source of voltage provides the operating voltage which is supplied to the screen electrode 59 of the oscillator tube by way of the connection to it through the resistor 86. In the arrangement shown, it will be understood that all voltages represented by the plus connections at various terminal points are understood as being so connected that the positive terminal connects as indicated and the negative terminal connects to ground to provide the direct current path, which has not been shown completed throughout for convenience of illustration.

20 The oscillator tube 51 so functions as to produce plate current saturation at the anode 83 during the positive half cycles. The result is that the plate voltage appearing at the plate or anode 83, under these circumstances, is essentially and, for all practical purposes, a square wave, as indicated by the wave form exemplified adjacent the tube output. This output wave is then fed or supplied through a differentiating circuit comprising the condenser 87 and resistor 88 connected to ground 21, and coupled to this differentiating circuit by way of condenser 89 is the control electrode 90 of a discharge tube 91. Through the utilization of the differentiating circuit, comprising the condenser 87 and the resistor 88, a narrow pulse, as indicated by the wave form adjacent the diagram, is developed to actuate the discharge tube. The discharge tube 91 is self biased by way of the resistor 92 and its plate or anode 95 connects by way of the resistor element 96 to the positive terminal of a source of voltage (not shown) which is connected to the point 97. The voltage source which connects at terminal 97 is then arranged to charge the condenser 99 through the charging resistor or output resistor of tube 91 so that a voltage wave appears across the condenser between the terminal 100 and ground which is in the general shape of a sawtooth.

25 This sawtooth wave has its relatively low slope portion representing an increase in voltage across the condenser plates built up by charging of the condenser 99 through the resistor 96. The steep slope or discharge portion of the condenser is occasioned during the period of conductivity within the discharge tube 91 as produced by the positive portion of the differentiated pulse that is applied to the control grid 90. Thus, sawtooth waves of a frequency which is directly related and equal to that of the oscillator 51 are developed to be applied to the output or power amplifier tube 101 by way of the coupling condenser 103, in known manner. In practice, the output tube

stantially similar to that shown in connection with the circuit of Fig. 2 and it will be seen from the curves adjoining the circuit diagram that the grid swing in the oscillator tube 51 produces essentially a square wave in the plate circuit of the tube 51. This wave is differentiated by the chosen relationship between the capacity 87 and the resistor 88 together forming a differentiating circuit until a wave form substantially like that indicated in Fig. 5 is obtained. The positive portion of this differentiated wave is sufficiently sharp that when it is applied to the control electrode of a discharge tube, such as the tube 91, for instance, a sawtooth of voltage is produced in the plate circuit of such a tube in substantially normal manner. The remaining operation may be considered to be as shown by the circuit of Fig. 2 and the block diagram of Fig. 1.

In what has been above stated, it will be noted that reference has been made to the utilization of a sync pulse of positive polarity being applied to the discriminator tube 35. This has been found to be extremely satisfactory in operation. However, as already pointed out, the system functions equally well where the sync pulse is of the opposite polarity and the control of the discriminator circuit and the application of control voltage to the grid 69 of the reactance tube 63 is in accordance with the principles hereinabove explained, as should now be apparent. For a circuit of the character hereinabove described, it will be apparent that the lock-in may occur within a reasonably wide range without in any way destroying the interlacing characteristics or without introducing objectionable noise effects in the pattern or raster traced by the scanning beam on the cathode ray tube target so that, notwithstanding the effects of noise, high apparent resolution is maintained.

The system hereinabove described has been set forth in such a way that the sync pulses *a* and/or *b*, for instance, have been applied to the detector unit 35 which includes the pair of rectifier elements so as to be in-phase (or in push-push) on each rectifier element. The illustration of the system, as above set forth, also provides for supplying the output of the sine wave oscillator unit 51 to the detector unit so that the oscillator output is applied in an out-of-phase (or in push-pull) manner on each of the pair of rectifier elements. It should be understood, however, that the system herein disclosed is capable of operating in such a way that the oscillator output is supplied to the separate sections of the detector unit in such a way that it reaches each of the rectifier elements in an in-phase (or push-push) manner. Similarly, under such condition, the sync or control pulses, which are derived from any supplied or control sync signal, are applied to the separate rectifier elements of the detector unit in an out-of-phase (or in push-pull) relationship with respect to each other. Under these circumstances the control pulse, which is applied to one of the separate rectifier units or paths, is preferably passed through an inverter to reverse its phase with respect to the pulse applied to the other rectifier path.

While a system of such type falls within the scope of the present invention, it, nevertheless, has been found generally to be desirable to follow the arrangement more explicitly set forth by the description of the invention as hereinbefore made in detail because it is usually easier to arrange the operation and to stabilize the control where the incoming control or sync pulse is supplied

in an in-phase manner (or in push-push) on the separate rectifier paths or elements in that no difficulties then are encountered in making the amplitude of the control sync pulses applied to each rectifier path equal.

It will further be appreciated from what has been above stated that the herein described circuit has been mentioned particularly in connection with the high speed line deflection (customarily termed the "horizontal deflection"). However, where the circuit constants or parameters are slightly modified to take care of a different frequency range, the system is also applicable for the low frequency frame or field deflection control (customarily termed the "vertical deflection"). It should, therefore, be understood that the application of the invention to one form of control system is supplied by way of illustration rather than limitation.

Various modifications, of course, may be made without departing either from the spirit or scope of the present invention.

Having now described the invention, what is claimed and desired to be secured by Letters Patent is the following:

1. In electronic apparatus wherein deflection voltages are to be developed to control the deflection of a cathode ray beam in synchronism with a remote control operation, means to derive control pulse energy subject to slight frequency and phase changes in accordance with a remote operation, a substantially normally stable local oscillator means for developing sinusoidal shaped oscillations at a frequency substantially coinciding with the average repetition frequency of the derived control pulses, a detector unit including a pair of unilaterally conducting devices, means simultaneously to apply the sinusoidal oscillations and the derived control pulses additively to the two unilaterally conducting devices with either the oscillations or the pulses being applied in push-pull manner and the other in push-push manner, means operative so that for a predetermined phase relationship existing between the control pulse repetition and the sine wave oscillations a predetermined output is derived from the detector unit and with phase shifts of the control pulse between a faster and a slower frequency of recurrence relative to the normal frequency of the said sine wave oscillator greater output voltages are developed by one or the other of the unilaterally conducting devices, reactance means to control the local oscillator frequency, means to modify the effective reactance of the said reactance means to cause an increase or a decrease in the local oscillator frequency in accordance with output variances of the unilaterally conductive devices due to frequency or phase increases or decreases in the control pulses as compared to the local oscillator frequency and phase, and means to control the deflection of a cathode ray beam under the influence of the developed sine wave energy and at a frequency coinciding therewith.

2. The apparatus claimed in claim 1 comprising, in addition, means to develop substantially square wave voltage pulses from and at the frequency of the said sine wave oscillator, a deflection control circuit including a storage element connected so as to be charged along a substantially linear path, means for differentiating the said square wave pulses to develop triggering pulses at a frequency corresponding to that of the sine wave developed by the oscillator, discharge tube means connected to shunt with the said storage

101 is usually a pentode or a tetrode and especially so where the system operates at line frequency. The triode illustrated is merely shown for convenience of illustration. The output tube supplies the output pulses to the primary winding 105 of the transformer 107 where the output load is in the form essentially of the output coil through which the positive potential for the output tube 101 is provided from a terminal point 103 which connects to a positive terminal of a voltage source (not shown). The secondary winding 109 of the output transformer connects at its ends to the output terminals 110 and 111 to which the suitable deflecting coils (not shown) are arranged to be connected in known manner.

Fig. 5 shows a modification of the circuit of Fig. 2 and like parts in each Figure are referred to by like reference numerals. Similar to the circuit arrangement of Fig. 2, the incoming sync pulses, preferably of positive polarity as indicated, are applied to the input terminal 11 and then fed in an in-phase manner upon each diode. In contrast to the direct connection between point 39 and the junction of resistors 48 and 49, as shown by Fig. 2 it has been found desirable in many instances to include more resistance at this point in the circuit, which resistance is provided by resistor unit 52. Likewise, in some instances it has been found desirable for increasing operational fidelity to apply a relatively low negative bias to the cathodes of the discriminator by connecting a suitable bias voltage at the terminal point 50.

As was explained in connection with the arrangement of Fig. 2, the oscillator tube 51 is connected in such a way that the oscillatory action takes place between the screen grid 59 and the cathode 58. It is usually preferable to couple the oscillator coil 53 rather tightly to the center tapped coil 41 which, like in the arrangement of Fig. 2, is preferably adjusted to a slightly off-resonance condition through the use of an indicated movable iron core.

As was explained in connection with Fig. 2, this arrangement is such that if the phase of the incoming sync pulses applied at terminal 11, for instance, is changed with respect to the sine wave output of the oscillator tube 51, as applied to the oscillator coil 53 and the coils 41, one or the other diode half of tube 35 will produce a greater voltage drop across either resistor 48 or resistor 49. It will be appreciated that if the greater drop of voltage takes place across the resistor 48 the voltage across the two diodes may be assumed to be positive, whereas if the greater voltage drop takes place across the resistor 49, the opposite or reverse condition may be assumed to exist. Accordingly, the voltage developed at the point 62 which is to be used to control a gain of the reactance tube 63 can vary from a positive value through zero to a negative value dependent upon the phase relationship of the incoming sync pulses and the sine wave output of the oscillator as affecting the discriminator tube unit 35.

In the arrangement shown by Fig. 5 the reactance tube 63 is connected in a slightly different manner with respect to the oscillator tube from that shown by Fig. 2. It will be seen that the oscillator tube 51 has its grid 57 connected to one end of the oscillator coil 53 and its screen grid 59 connected to the other end of the oscillator coil, which end is grounded at 21, through the condenser 61. The oscillator tube cathode 58 connects to an intermediate point of the coil 53. The reactance tube is so connected that its plate 79

which is supplied by positive voltage from a terminal 72 through the indicated resistor connects to one end of the oscillator coil by way of condenser 81. The cathode of the reactance tube 63 connects to the junction point 64 between the oscillator tank circuit condenser 56 and resistor 60 which are serially connected across the oscillator coil 53. In this way, quadrature voltage is supplied by conductor 125 to the reactance tube, as indicated.

Under these conditions it will be appreciated that the D. C. output available at the point 62 is now supplied by way of the conductor 66 to the grid or control electrode 69 of the reactance tube and superimposed upon a fixed bias applied to the same electrode through the filter comprising the combination of the resistor 67 shunted by condenser 114 and across which the condenser 115 connects to ground. The reactance tube operates to provide a reactive plate current by virtue of the cathode input sine wave voltage obtained from across the resistor 60 which is in series with the oscillator tank capacitor 56, as above explained. Any changes in the D. C. voltage applied in conductor 66 to the grid 69 of the reactance tube by virtue of voltage changes appearing at point 62 tend to provide changes in the transconductance of the reactance tube 63 and thus bring about changes in the reactive plate current, since the plate 79 of the tube 63, as above explained, connects with the oscillator tank coil 53 by way of the condenser 81.

Accordingly, as was the case with the circuit of Fig. 2 where the phase of the oscillator is not in proper relationship to the incoming sync pulse applied at the terminal 11, the D. C. information obtained from the discriminator will correct the oscillator frequency and cause it to coincide with the control pulses.

In the arrangement shown by Fig. 5, the filter combination comprising the resistor 67 and the condensers 114 and 115 is such that the two condensers form a voltage divider to attenuate rapid changes in direct current, such as are produced by the vertical sync pulses or bursts of interference and, thus, this further tends to stabilize the oscillation frequency. It has been found that where the transmitted sync signal pulses are not sufficiently stable, which is a condition that, unfortunately, exists at times, a relatively flat response to fluctuations in the D. C. information is required. This is obtained in this circuit by a proper determination of the ratio of the size of the condensers 114 and 115.

In addition, where any considerable degree of instability of the incoming control pulse frequency exists, it is often desirable to provide further control measures. To this end, the filter combination above described is provided with an additional shunting capacity 116 of which one terminal connects to the ungrounded terminal of the capacity 115 and the other terminal connects to the switch arm 118. Under normal operating conditions where there is relatively good stability in the incoming sync pulses the switch arm 118 is placed in its upper or open position against the terminal 122, as shown, but where considerable instability in the incoming sync pulses is found to exist, the switch arm 118 is moved to the lower or closed terminal 120 position whereby the condenser 116 is placed in shunt with the condenser 114 and the response of the circuit increased.

The manner of deriving a substantially square wave output from the oscillator tube 51 is sub-

element, connecting circuit elements for applying the triggering pulses to the discharge tube whereby the stored charges are dissipated and a substantially sawtooth voltage wave of a frequency corresponding to the sine wave oscillator is developed across the storage means, and a load circuit including the deflecting elements of the cathode ray tube connected to receive the said developed sawtooth voltage wave for deflecting the cathode ray beam.

3. In electronic apparatus wherein deflection voltages are to be developed to deflect a cathode ray beam under the control of a series of control energy pulses subject to slight frequency and phase changes, a local oscillator for normally developing substantially stable sinusoidal oscillations at a frequency substantially coinciding with the normal desired repetition frequency of the control pulses, a detector unit including a pair of unilaterally conducting devices, means simultaneously to apply the sinusoidal oscillations to the two unilaterally conductive devices as two out-of-phase waves, means to apply the control pulses to each unilaterally conducting device in an n-phase relationship whereby at times of frequency and phase identity between the control pulse repetition and the sine wave oscillations a predetermined output is derived from the detector unit and with phase shifts of the control pulse between a faster and a slower frequency of recurrence than that of the said sine wave oscillations the output voltages developed by one or the other of the unilaterally conducting devices become unequal and provide a changed value control voltage, reactive means to control the local oscillator frequency, means to modify the effective reactance of the said reactive means to cause an increase or a decrease in the local oscillator frequency in accordance with the output voltage variances of the rectifier elements, and means to control the deflection of a cathode ray beam under the influence of the developed sine wave energy and at a frequency coinciding therewith.

4. The apparatus claimed in claim 3 comprising, in addition, means to develop substantially square wave voltage pulses from and at the frequency of the said sine wave oscillator, a deflection control circuit including a storage element connected with a source of voltage so as to be charged along a substantially linear path, means for differentiating the said square wave pulses to develop triggering pulses at a frequency corresponding to that of the sine wave developed by the oscillator, discharge tube means connected in shunt with the said storage element, a connecting circuit for applying the triggering pulses to the discharge tube whereby the stored charges are dissipated and the voltage across the storage element is of substantially sawtooth form and of a frequency corresponding to that of the sine wave oscillator, and a load circuit including the deflecting elements of the cathode ray tube connected to receive the said developed sawtooth voltage wave for deflecting the cathode ray beam.

5. The apparatus claimed in claim 2 comprising, in addition, a deflection circuit having included therein means to develop substantially sawtooth form electrical wave energy for use in deflecting a cathode ray beam in a selected direction, and means to derive triggering pulses from said oscillator output to initiate an operation of said deflection circuit.

6. In television apparatus wherein deflection voltages are to be developed to control the deflec-

tion of a cathode ray scanning beam in synchronism with a remote scanning operation, and wherein the scanning control pulse energy to control such operation is subject to slight frequency changes as a result of a remote operation, a normally stable local oscillator means for developing substantially sinusoidal shaped oscillations at a frequency substantially coinciding with the average repetition frequency of the control pulses, a detector unit including a pair of unilaterally conducting devices, means simultaneously to apply the sinusoidal oscillations to the two unilaterally conducting devices in push-pull fashion, means to apply the scanning control pulses in an in-phase manner to each unilaterally device whereby at times of frequency and predetermined phase identity between the control pulse repetition and the sine wave oscillations a predetermined output is derived from the detector unit and with phase shifts of the control pulse between a faster and a slower frequency of recurrence than that of the said sine wave oscillations greater output voltages are developed by one or the other of the unilaterally conducting devices, a reactance tube unit connected to control the local oscillator frequency, means to vary the gain of the said reactance tube unit to modify the effective reactance thereof and thereby to cause an increase or a decrease in the local oscillator frequency in accordance with output variances of the individual unilaterally conducting devices due to phase differences between the applied control pulses and the generated sine waves which represent a relative frequency increase or decrease of the control pulses, and means to control the deflection of a cathode ray beam under the influence of the developed sine wave energy and at a frequency coinciding therewith.

7. In television apparatus wherein deflection voltages are to be developed to control the deflection of a cathode ray beam in synchronism with received control synchronizing pulses which are subject to frequency repetition changes in accordance with a remote operation, a detector unit including a pair of unilaterally conducting devices, a local oscillator including a tank circuit wherein substantially sinusoidal oscillations are developed at a frequency substantially coinciding with the normal repetition frequency of the developed control pulses, means simultaneously to apply the sinusoidal oscillations to the two unilaterally conducting devices as two out-of-phase waves, means to apply the control synchronizing pulses to each unilaterally conducting device in like phase relationship whereby at times of frequency identity between the control pulse repetition and the sine wave oscillations a predetermined output is derived from the detector unit and with phase shifts of the control pulse between a faster and a slower frequency of recurrence than that of the said sine wave oscillations greater output voltages are developed by one or the other of the rectifier elements, reactance means connected in shunt to the oscillator tank circuit to control the local oscillator frequency, means to modify the effective reactance of the said reactance means to cause an increase or a decrease in the local oscillator frequency in accordance with output variances of the unilaterally conducting devices due to frequency increases or decreases in the control pulses, and means to control the deflection of a cathode ray beam under the influence of the developed sine wave energy and at a frequency coinciding therewith.

8. The combination claimed in claim 7 wherein the said reactance means comprises a thermionic tube, and means to supply a control voltage to said tube in proportion to variances in the output of the said unilaterally conducting device so as thereby to alter the tube transconductance and thereby change the reactive component of the oscillator tank circuit.

9. A deflection circuit for deflecting the electron beam developed within a cathode ray tube which comprises a substantially stable frequency local oscillator for developing sine wave voltages of a frequency corresponding to that frequency at which the said beam is to be deflected, means coupled to the oscillator to develop substantially square wave voltage pulses from and at the frequency of the said sine wave oscillator, a deflection control circuit including a capacity element connected with a source of voltage so as to be charged along a substantially linear path, means for differentiating the said developed sine wave frequency square wave pulses to derive triggering pulses to time the operation of the deflection control circuit, discharge tube means connected in shunt with the said capacity element, means for applying the triggering pulses to the discharge tube whereby the stored charges in the capacity element are dissipated and a substantially sawtooth voltage wave of a frequency corresponding to the sine wave oscillator is developed, a load circuit including the deflecting elements of the cathode ray tube connected to receive the said developed sawtooth voltage wave for deflecting the cathode ray beam, and reactance tube means to vary the frequency of the sine wave oscillator under the influence of supplied control signals so that the deflection is stabilized with the supplied signals.

10. In cathode ray tube apparatus wherein an electron beam is to be deflected in accordance with a remote origin control effect, a substantially stable frequency local oscillator for generating substantially sine wave output voltages, means to receive the output from the oscillator and to develop therefrom substantially square wave voltage pulses at the frequency of the said oscillator, a capacity element, a source of voltage connected to said capacity element to charge it along a substantially linear path, means for differentiating the said developed square wave pulses to derive triggering pulses occurring at a frequency corresponding to the sine wave frequency of the oscillator, discharge tube means connected in shunt with the said capacity element, means for applying the triggering pulses to the discharge tube whereby the stored charges in the capacity element are abruptly reduced to a substantially minimum value and a substantially sawtooth voltage wave occurring at a frequency corresponding to the sine wave oscillator frequency is developed across the said capacity element, a load circuit including the deflecting elements of the cathode ray tube apparatus connected to receive the said developed sawtooth voltage wave for deflecting the cathode ray beam, a reactance tube unit connected with the oscillator to change the oscillator frequency in accordance with varying current flow through the tube unit providing a change in the reactive effect of the tube unit on the oscillator in accordance with phase relationship between a supplied control pulse and the instantaneous oscillator frequency whereby the oscillator frequency is caused to follow supplied control pulses and to stabilize the deflection therewith.

11. A circuit for providing deflecting wave energy to be supplied to the deflecting elements associated with a cathode ray tube for controlling the deflection of the cathode ray beam in synchronism with a remote effect which comprises means including a capacity element connected with a voltage source to be charged and a discharge tube connected therewith for discharging the capacity during periods of conduction there-in so that substantially sawtooth wave energy is developed so as to be supplied to the beam deflecting means for deflecting the cathode ray beam, means for developing synchronizing energy pulses of a frequency at which it is desired that the said deflection shall occur, a local oscillator including an oscillatory circuit wherein substantially sine wave voltages are developed, means associated with the oscillator for deriving triggering pulses from the said developed sine wave voltages so as repeatedly to trigger the discharge tube at time periods coinciding with repetitions of like portions of the generated sine waves, a phase detector unit for making a phase comparison between the frequency of repetition of the developed sine waves and the developed synchronizing pulse energy so that voltages are derived from the detector which are proportional to increases and decreases in the rate of recurrence of the developed synchronizing pulses as compared with the sine wave frequency, and a reactance means connected to the oscillatory circuit of the oscillator and also connected to receive and respond to output voltages from the said detector to produce a reactance change serving to modify the frequency of the local oscillator to a value at which it substantially coincides with the frequency of recurrence of the developed pulses so that the deflection control sawtooth energy wave is developed at the frequency of the synchronizing pulses.

12. A circuit for providing deflecting wave energy to be supplied to deflecting means associated with a cathode ray device for controlling the deflection of the cathode ray beam developed there-in in synchronism with a remote effect which comprises means including a storage element and a discharge tube connected therewith for developing substantially sawtooth wave energy serving to provide the control of the beam deflecting means, means for deriving control energy pulses occurring at a frequency at which it is desired that the said beam deflection shall occur, a local oscillator for developing substantially sine wave output voltages, means for deriving triggering pulses from the said sine wave voltages so as to trigger the discharge tube at a rate corresponding to frequency of occurrence of the sine wave, means for developing two out-of-phase like frequency sine waves from the said oscillator, means for additively and separately combining the developed pulses occurring at the desired rate of deflection with each of the said out-of-phase waves, peak detector means for each of the combined waves to derive therefrom output voltages which vary in time relationship in substantial proportion to phase variances occurring between the said two waves and the said control pulses, and reactance tube means having its output connected to the oscillator and its input connected to receive the output voltages from the detector means to vary the gain of the reactance means and thereby to vary the effective reactance effect on the oscillator so that oscillation frequency thereof is subject to a controlled variance in a

direction to stabilize it with the frequency of the derived control pulse energy.

13. A circuit for providing deflecting wave energy to be supplied to deflecting means for controlling the deflection of a cathode ray beam developed within a cathode ray tube in synchronism with remote effect which comprises means including a storage element and a discharge tube connected thereto for developing substantially sawtooth wave energy adapted to be supplied to control the beam deflecting means, means for deriving pulse energy occurring at a frequency at which it is desired that the said deflection shall occur, a local oscillator having a tank circuit wherein substantially sine wave voltages occur, means for deriving triggering pulses from the said sine wave voltages so as to trigger the discharge tube at a rate corresponding to the sine wave frequency, means for developing two out-of-phase like frequency sine waves from the said oscillator, means for additively and repeatedly combining each of the derived pulses representing the desired deflection frequency and the said out-of-phase waves, a phase detector unit for making a phase comparison between the frequency of repetition of the developed sine waves and the developed pulse energy so that output voltages are derived from the detector which are proportional to advanced and retarded phase relationships between the derived control pulse energy and the sine wave frequency, a reactance tube means having its output connected to the oscillator and its input connected to respond both to quadrature voltage derived from the oscillator and the output of which serves to vary the reactance tube gain and provide a reactive current to modify the frequency of the local oscillator to a value at which it substantially coincides with the frequency of recurrence of the developed pulses.

14. A circuit for providing deflecting wave energy to be supplied to the electron beam deflecting means of a cathode ray tube for controlling the deflection of the developed beam in synchronism with a remote effect which comprises a local oscillator having a tank circuit wherein substantially sine wave voltages are developed, means for deriving triggering pulses from the sine wave voltages for initiating deflection of the cathode ray beam in substantial frequency coincidence with the sine wave frequency developed by the local oscillator, means for deriving voltage pulses at a pulse repetition frequency corresponding to that of a remote source which represents the frequency at which it is desired the said deflection shall occur, a detector unit including a pair of unilaterally conducting devices, means simultaneously to apply the developed sinusoidal voltages and the derived control voltage pulses additively to each unilaterally conducting device of the detector unit so that one of the two voltages is applied to each unilaterally conducting device in an out-of-phase manner and the other of the two voltages is applied to each unilaterally conducting device in an in-phase manner so that for a predetermined phase relationship existing between the two voltages a predetermined voltage output is derived from the detector unit and with phase shifts of the derived control pulse voltage between a faster and a slower frequency of recurrence than that of the normal frequency of the sine wave voltage greater or lesser output voltages are derived from each unilaterally conducting device of the detector unit, a reactance tube unit having its output coupled across the oscillator tank circuit, means to supply voltage from the oscillator tank circuit to an input electrode of the reactance tube and in a predetermined phase relationship with respect to the voltage supplied from the oscillator to the detector unit, means including a filter combination comprising resistance and capacity elements for applying a predetermined bias voltage on the input of the reactance tube to control the current normally flowing therethrough, and means to modify the voltage bias upon the reactance tube in accordance with variances in output from the detector unit so as thereby to vary the transconductance of the reactance tube and thereby vary the reactive current effective upon the oscillator tank circuit and cause the oscillator frequency to vary in a direction to coincide with that of the derived control pulse signal voltages.

put coupled across the oscillator tank circuit, means to supply voltage from the oscillator tank circuit to an input electrode of the reactance tube means and in a predetermined phase relationship with respect to the voltage supplied from the oscillator to the detector unit, means for applying a predetermined bias voltage on the input of the reactance tube to control the current normally flowing therethrough, and means to modify the voltage bias upon the reactance tube in accordance with variances in output from the detector unit so as thereby to vary the transconductance of the reactance tube and thereby vary the reactive current effective upon the oscillator tank circuit and cause the oscillator frequency to vary in a direction to coincide with that of the derived control pulse signal voltages.

15. A circuit for providing deflecting wave energy to be supplied the electron beam deflecting means of a cathode ray tube for controlling the deflection of the developed beam in synchronism with a remote effect which comprises a local oscillator having a tank circuit wherein substantially sine wave voltages are developed, means for deriving triggering pulses from the sine wave voltages for initiating deflection of the cathode ray beam in substantial frequency coincidence with the sine wave frequency developed by the local oscillator, means for deriving voltage pulses at a pulse repetition frequency corresponding to that of a remote source which represents the frequency at which it is desired the said deflection shall occur, a detector unit including a pair of unilaterally conducting devices, means simultaneously to apply the developed sinusoidal voltages and the derived control voltage pulses additively to each unilaterally conducting device of the detector unit so that one of the two voltages is applied to each unilaterally conducting device in an out-of-phase manner and the other of the two voltages is applied to each unilaterally conducting device in an in-phase manner so that for a predetermined phase relationship existing between the two voltages a predetermined voltage output is derived from the detector unit and with phase shifts of the derived control pulse voltage between a faster and a slower frequency of recurrence than that of the normal frequency of the sine wave voltage greater or lesser output voltages are derived from each unilaterally conducting device of the detector unit, a reactance tube unit having its output coupled across the oscillator tank circuit, means to supply voltage from the oscillator tank circuit to an input electrode of the reactance tube and in a predetermined phase relationship with respect to the voltage supplied from the oscillator to the detector unit, means including a filter combination comprising resistance and capacity elements for applying a predetermined bias voltage on the input of the reactance tube to control the current normally flowing therethrough, and means to modify the voltage bias upon the reactance tube in accordance with variances in output from the detector unit so as thereby to vary the transconductance of the reactance tube and thereby vary the reactive current effective upon the oscillator tank circuit and cause the oscillator frequency to vary in a direction to coincide with that of the derived control pulse signal voltages.

16. A circuit for providing deflecting wave energy to be supplied the electron beam deflecting means of a cathode ray tube for controlling the deflection of the developed beam in synchronism with a remote effect which comprises a local

oscillator having a tank circuit wherein substantially sine wave voltages are developed, means for deriving triggering pulses from the sine wave voltages for initiating deflection of the cathode ray beam in substantial frequency coincidence with the sine wave frequency developed by the local oscillator, means for deriving pulses at pulse repetition frequency corresponding to that of a remote source which represents the frequency at which it is desired the said deflection shall occur, a detector unit including a pair of unilaterally conducting devices, means simultaneously to apply the developed sinusoidal voltages and the derived control voltage pulses additively to each unilaterally conducting device of the detector unit so that one of the two voltages is applied to each unilaterally conducting device in a push-pull manner and the other of the two voltages is applied to each of the unilaterally conducting devices in a push-push manner so that for a predetermined phase relationship existing between the two voltages a predetermined voltage output is derived from the detector unit and with phase shifts of the derived control pulse voltage between a faster and a slower frequency of recurrence than that of the normal frequency of the sine wave voltage greater or lesser output voltages are derived from each unilaterally conducting device of the detector unit, a reactance tube unit having its output coupled across the oscillator tank circuit, means to supply voltage from the oscillator tank circuit to an input electrode of the reactance tube means and in a predetermined phase re-

lationship relative to the voltage supplied to the detector unit, means including a filter combination comprising resistance and capacity elements for applying a predetermined bias voltage on the input of the reactance tube to control the current normally flowing therethrough, means to modify the voltage bias upon the reactance tube in accordance with variances in output from the detector unit so as thereby to vary the transconductance of the reactance tube and thereby vary the reactive current effective upon the oscillator tank circuit and cause the oscillator frequency to vary in a direction to coincide with that of the derived control pulse signal voltages, and switching means to modify the capacity value of the bias setting time constant circuit to control thereby the rate at which the effectiveness of the detector unit applied to the reactance tube to vary the gain thereof may be varied.
